UNITED STATES PATENT OFFICE.

JACOB BEESLEY, OF PHILADELPHIA, PENNSYLVANIA, ASSIGNOR TO DAVID STUART AND RICHARD PETERSON, BOTH OF SAME PLACE.

DESIGN FOR A COOK-STOVE.

SPECIFICATION forming part of Design No. 12,248, dated May 10, 1881.

Application filed May 10, 1880. Term of patent 7 years.

To all whom it may concern:

Be it known that I, JACOB BEESLEY, a citizen of the United States, and a resident of Philadelphia, Pennsylvania, have invented and produced a new and original Design for Stove or Range Doors or Plates, of which the following is a specification, reference being had to the view in the accompanying drawing, which represents a perspective view of a stove with my newly-
designed door or plate applied thereto.

A is the side of the cook-stove and B a door on the side.

The main feature of my design consists of the representation of a miner, as shown on this door.

Around the edge of the door B is a panel, and within this panel, at the four corners, are

four pyramidal-shaped ornaments, T, connected with each other by lines of beading O. Within the frame thus formed is a raised centerpiece, F, representing a view of the interior of a mine, with the miner at work, using his pick and having other mining implements about him.

The ornamentation on the panel C and doors D forms no part of my present design.

I claim—

A design for the ornamentation of a stove or range door or plate, substantially as described and shown.

JACOB BEESLEY.
